UNITED STATES PATENT OFFICE.

LAFAYETTE C. VAN DUZER, OF NATIONAL SOLDIERS HOME, HAMPTON, VIRGINIA.

AIRSHIP.

1,170,367.

Specification of Letters Patent.

Patented Feb. 1, 1916.

Application filed April 27, 1915. Serial No. 24,286

To all whom it may concern:

Be it known that I, LAFAYETTE C. VAN DUZER, a citizen of the United States, residing at National Soldiers Home, Hampton, 5 and State of Virginia, have invented new and useful Improvements in Airships, of which the following is a specification.

My invention relates to airships of that kind embodying the principles of the aero- 10 plane and dirigible aerostat, and one of its objects is to provide a machine of this character in which effective means are employed for sustaining the machine by the buoying action of a volume of gas and the supporting 15 action of aeroplane surfaces.

A further object of the invention is to provide a machine embodying a substantially cigar shaped car suitably partitioned to provide cabins and compartments and having 20 extending axially therethrough an air tube or wind tunnel, with which the frame of the car is connected to secure great strength and durability, suitable propelling means being provided for circulating air through the 25 tube or tunnel by means of which greater sustaining and propulsive powers are obtained.

A further object of the invention is to provide an airship embodying certain other 30 features of construction increasing the strength, durability and general efficiency of airships of this character.

The invention consists of the features of construction, combination and arrangement 35 of parts herein fully described and claimed, reference being had to the accompanying drawings in which:-

Figure 1 is a side elevation of an airship embodying my invention. Fig. 2 is a vertical longitudinal section of the same. Fig. 3 is a top plan view. Fig. 4 is a front elevation. Fig. 5 is a vertical transverse section.

In carrying my invention into practice, I provide an airship comprising a substantially 45 cigar-shaped car 1, which is approximately of circular form at the center and thence tapers uniformly toward its opposite ends. The car is in the form of a hollow body, consisting of a casing 2 of fabric, sheet metal or 50 other suitable material secured to a skeleton frame foundation 6, which terminates at its ends in annular disks or heads 7. Extending

axially through the body is a wind tube or air tunnel 8, which is rigidly fastened at its ends to the heads 7 and has its bore or passage in registry with the openings therein, the said tube or tunnel being connected with the frame work 6 by bracing elements 9 whereby a structure of great strength and durability is obtained.

Extending through and suitably journaled within the tube or tunnel 8 are shafts 10 and 11, which are driven in opposite directions by chain and sprocket or other suitable sets of gearing 12 and 13 from one or more driving motors 14. These shafts project at the front and rear of the body and are journaled at their projecting ends in bearing brackets 14'. Carried by the respective shafts are fans or propellers 15 and 16, 70 which are arranged to respectively rotate within the front and rear ends of the wind tube or column and operate to produce a suction whereby, in the travel of the craft, air is drawn into the wind column, compressed to a certain degree and thence projected in a comparatively dense volume at the rear of the craft, the projected dense column of the air at the rear serving by its reaction to give both a propelling and a sus- 80 taining effect. In practice, the propellers are preferably driven, as stated, in opposite directions, and the rear propeller is driven at a higher rate of speed than the front propeller, so as to insure the rapid discharge of 85 the condensed air and to prevent over accumulation of air entering the wind tube through the force of travel of the craft and the suction produced by the propellers.

The interior of the car or body 1 is partitioned or divided into any suitable number of compartments, a pilot's compartment 17, and engine or power plant compartments 18 and 19 being shown in the present instance. From the remaining space within the car is 90 air which is expelled or exhausted, and this space is filled with bags or balloonets 20 containing hydrogen or other gas lighter than air, by which the sustaining action of an aerostat sufficient to lift a part of the weight 95 of the craft is obtained.

Suitably secured to the body are upper and lower central, vertical, longitudinally extending fins or vanes 21 and 22 which may

be of any suitable construction and braced in any preferred manner. In practice the fin or vane 21 may in some cases be omitted, but the fin or vane 22 is employed at all 5 times and serves as a keel to hold the craft to its course and also as a support for suitably cushioned launching and landing wheels 22'. It may also form a support for a center board or suitable hydroplane 10 surface, when the craft is intended to be operated upon water. Extending from the sides of the body are front and rear sets of sustaining planes 24 and 25, which are inclined or curved to present the desired angle 15 of incidence and secure the desired lifting pressure. The front and rear planes 24 and 25 of each set are independent, and the front edges of the rear planes 25 may be overlapped by the rear edges of the front planes 24 so as to provide a proper interposed air 20 clearance space. The wings are pivoted to tilt vertically on horizontal transverse axes 26, so that they may be employed for steering or stability purposes when desired, or so 25 that their working angle may be increased or diminished as occasion may require. They operate when the machine is propelled through the air at a given speed to sustain the greater part of the weight of the craft, 30 so that, through the additional sustension afforded by the balloonets, a craft having great lifting capacity will be produced. Any suitable means for adjusting each wing 35 may be employed; but in the present instance I have shown cords or cables 27 connected from above and below to the free edge of each plane, and thence passing over guide pulleys 28 to the interior of the craft and being connected with a winding drum 40 or the like 29, by means of which the respective wings may be properly adjusted in unison.

In addition to the propelling means previously described, I preferably employ upper 45 and lower forward propellers 30 and 31 and upper and lower rear propellers 32 and 33, which propellers are mounted upon horizontal transverse shafts and driven from the motors in any suitable manner. The front 50 and rear sets of propellers are respectively arranged at points between the center of the body and the reduced ends thereof, and the lower propellers 31 and 33 are intended in practice to be submerged when the craft 55 rests upon the surface of a body of water so that they may be employed as marine propellers to drive the craft through the water. While any suitable type of propelling and steering means may be employed, I have 60 shown herein front and rear vertical rudders 34 and front and rear horizontal rudders 35, which rudders are respectively connected by sets of cords or cables 36 and 37 with controlling devices 38 and 39 within 65 the pilot's compartment by means of which

said rudders may be easily and conveniently adjusted. Inasmuch as both ends of the craft are formed alike, and are provided with similar propelling and steering devices, by suitably controlling and driving 70 the propelling devices the craft may be backed or driven with either end ahead as the bow portion, the advantages of which will be evident without recitation.

The craft may be of any desired length, 75 diameter or spread, and by reason of the construction described it may be operated at great speed and will have a large amount of lifting capacity, and by adapting the balloonets to support the load weight the 80 craft may be caused to hover over any given point, rendering it of great value in making observations for military and other purposes, etc.

I claim:—

1. An airship including a substantially cigar-shaped hollow body, a rigid wind tunnel extending axially through the body, suction fans at the front and rear of the tunnel, cabins within the body, balloonets filling the spaces between the wind tunnel and body remaining unoccupied by the cabins, counterpart rudders at opposite ends of the body, sustaining wings at the sides of the body, propellers at the front and rear of the body, and means for driving the fans and propellers. 90

2. An airship including a substantially cigar-shaped hollow body, a wind tunnel extending axially through the body, suction fans at the front and rear of the tunnel, a vane depending from and extending longitudinally of the bottom of the body, sustaining wings at opposite sides of the body, propellers at the front and rear of the body on opposite sides thereof, said propellers being arranged in upper and lower front and rear working pairs, and means for driving the suction fans and operating the said propellers. 100

3. An airship including a substantially cigar-shaped body, a tunnel extending axially through the body, suction fans at the front and rear of the tunnel, sustaining wings arranged at opposite sides of the body, propellers at the front and rear of the body on opposite sides thereof, said propellers being arranged in upper and lower front and rear working pairs, and means for driving the suction fans and operating 115 the said propellers. 120

4. An airship including a substantially cigar shaped hollow body, a wind tunnel extending axially through the body, suction fans at the front and rear of the tunnel, a 125 vane depending from and extending longitudinally of the bottom of the body, sustaining wings arranged in pairs in following order at opposite sides of the body, means for adjusting said wings to different 130

working angles, propellers at the front and rear of the body on opposite sides thereof, said propellers being arranged in upper and lower front and rear working pairs, and
5 means for driving the suction fans and operating the said propellers.

In testimony whereof I affix my signature in presence of two witnesses.

LAFAYETTE C. VAN DUZER.
